UNITED STATES PATENT OFFICE.

JOHN METCALFE, OF BRANTFORD, ONTARIO, CANADA, ASSIGNOR OF ONE-HALF TO CHARLES CHAMPION, OF SAME PLACE.

BUGGY-TOP.

SPECIFICATION forming part of Letters Patent No. 340,809, dated April 27, 1886.

Application filed February 6, 1886. Serial No. 191,028. (No model.)

To all whom it may concern:

Be it known that I, JOHN METCALFE, a subject of the Queen of Great Britain, residing at the city of Brantford, in the county of Brant, 5 in the Province of Ontario, Canada, have invented an Improved Device for Adjusting Buggy-Tops, of which the following is a specification.

This invention relates to improvements in devices for adjusting buggy-tops; and it consists in the peculiar combinations, and the novel construction and arrangement of parts, as more fully hereinafter described and claimed.

Figure 1 is a perspective view showing a 15 buggy-top provided with my improved device raised. Fig. 2 is a perspective view of the top folded. Fig. 3 is a detail of my device for adjusting the top.

A represents the front joint, and B the back 20 joint. The eye *a* of the front joint has a square hole to fit over the square end of the hollow sleeve or spindle C. The inside end of this sleeve C has a handle, D, fixed to it. The eye *b* of the back joint, B, has a square hole 25 which fits over a square formed on the spindle E, which passes through the sleeve C, and has a handle, F, fixed to its inside end, as shown. Both the handles D and F are accessible to

the occupant of the buggy, who, by pressing upon either one or other of these handles, may 30 adjust the front of the top or lower it entirely back, as circumstances require; and he can perform this service without moving off his seat.

I have shown in the drawings, by dotted 35 lines, the position of the top when the front is folded back. It will, of course, be understood that the front joint might be connected to the spindle E, and the back joint, B, to the sleeve C, the effect in either case being the same. 40

What I claim as my invention is—

The front joint, A, provided with eye *a*, having square hole, and the hollow sleeve G, having square end to engage the hole in said eye, combined with the back joint, B, having eye *b*, 45 provided with square hole, the spindle E, having square end engaging the hole in said eye *b*, the said spindle passing through the hollow sleeve, and the handles D F, fixed to the ends of the sleeve C and spindle E, respectively, 50 substantially as herein shown and described.

Brantford, January 25, 1886.

JOHN METCALFE.

In presence of—

CHARLES CHAMPION,
JOSEPH MURPHY.
